CLAIM

The ornamental design for an interior rearview mirror of automobile, as shown and described.

DESCRIPTION

FIG. 1 is a perspective view of an interior rearview mirror of automobile showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The dashed or broken lines shown in the drawings depict portions of the interior rearview mirror of automobile in which the design is embodied that form no part of the claimed design.
